DESIGN FOR A HAT ORNAMENT OR SIMILAR ARTICLE

Samuel Antenberg, Brooklyn, N. Y.

Application December 10, 1936, Serial No. 66,458

Term of patent 3½ years

To all whom it may concern:

Be it known that I, Samuel Antenberg, a citizen of the United States, residing in the Borough of Brooklyn, county of Kings, city of New York, and State of New York, have invented a new, original, and ornamental Design for a Hat Ornament or Similar Article, of which the following is a specification, reference being had to the accompanying drawing, forming a part thereof.

The characteristic feature of the design resides in the contrasting appearance of a braid superimposed upon a feather of contrasting color.

I claim:

The ornamental design for a hat ornament or similar article as shown and described.

SAMUEL ANTENBERG.
